(57) **CLAIM**

The ornamental design for a tape measure, as shown and described.

DESCRIPTION

FIG. 1 is a perspective view of the tape measure showing our new design;

FIG. 2 is a front view of the tape measure of FIG. 1;

FIG. 3 is a right side view of the tape measure of FIG. 1;

FIG. 4 is a left side view of the tape measure of FIG. 1;

FIG. 5 is a rear view of the tape measure of FIG. 1;

FIG. 6 is a top plan view of the tape measure of FIG. 1;

FIG. 7 is a bottom plan view of the tape measure of FIG. 1;

FIG. 8 is a perspective view taken generally from the bottom side thereof of a second embodiment of the tape measure with the front, rear and top plan views being substantially the same as FIGS. 2, 5 and 6, respectively;

FIG. 9 is a left side view of the embodiment of FIG. 8 with the right side view being the mirror image thereof; and,

FIG. 10 is a bottom plan view of the embodiment of FIG. 8.
